UNITED STATES PATENT OFFICE

2,093,515

WALL SCUPPER

Arthur J. Filkins, Chicago, Ill.

Application August 24, 1935, Serial No. 37,619

8 Claims. (Cl. 182—26)

This invention relates in general to a roof or wall drain for buildings and is commonly installed in an outer wall thereof for the purpose of providing an emergency or other discharge 5 for water or other liquid.

An important object of the invention is in the provision of an easily opening gate which has one or more pivoted flaps immediately opened by a rush of water from the inside.

10 A further object of the invention is in the provision of a protective grating on the inside and a package guard at the top which prevent an obstructing box or package from being placed too close to the inlet which would tend to obstruct the opening thereof.

A further object of the invention is in the provision of self-closing or gravity gates which are automatically closed and remain in closed position when not in use.

20 Other objects of the invention will appear hereinafter, the preferred construction being illustrated in the accompanying drawing, in which,

Fig. 1 is a top plan view of a structure in accordance with this invention;

25 Fig. 2 is a sectional view of the scupper as applied to a wall;

Fig. 3 is a face view of the scupper; and

Fig. 4 is a fragmentary perspective of a roof drain scupper discharge.

30 A scupper of this kind is installed flush with the lower edge of a roof or floor, it extends through the wall thereof and has a discharge at the opposite side with one or more gates therein and usually at the discharge end, which are immediately opened by a rush of water from the inside to provide an escape for water or other liquid in the case of a fire, the accidental breaking of a pipe, or any other emergency of this kind which may occur in a building, and will prevent the accumulation of a damaging amount of liquid.

Referring now more particularly to the drawing, a metal casing consisting of a substantially straight portion 10 and a connected outwardly flared portion 11 are installed in an outer or partition wall 12 of a building with the inner edge of the casing substantially at the top level of a roof or floor 13, the lower side or edge 14 of the casing being inclined downwardly from the floor 50 so that any water or other liquid on top of the floor will flow through the casing to the discharge end thereof.

The outwardly flaring portion has an upward offset 15 and at the sides of this flaring portion 55 are installed gates 16 each mounted at the in-

ner edge upon an inclined hinge pin 17 so that each gate tends to swing forwardly to close the front of the casing, and when swung rearwardly it engages the wall of the outwardly flaring portion 11 to offer no obstruction to liquid passing 5 therein.

A front or grating plate 20 is commonly provided to fit over the inlet end of the scupper and has a marginal rim for attachment to the end of the casing and a number of spaced vertical bars 10 21 to prevent any large obstruction from being inserted in the inlet to obstruct it in case of a fire. This front plate has rearward hinge projections 22 and 23 in which the gates 16 are mounted upon the hinge pins 17 and the projections are disposed with respect to each other as clearly shown so that the hinge pins 17 are inclined inwardly and forwardly at the top with respect to the sides of the plate 20 so that the natural tendency of the gate 16 pivoted at the 20 sides of the plate is to close inwardly and forwardly and to remain in this closed condition, easily balanced, so that a very slight rush of 25 water or other liquid will tend to open the gate and to maintain it in open position. For convenience in assembling and attaching the casing and assembling the parts therein, the top is 30 separately removable and a fastening bolt 24 extends from the bottom through the top and has a nut 25 for securing the top in place. At the front of the top are projections 26 near the sides thereof which are seated in corresponding notches 27 at the upper edges of the front plate 20, and with a downwardly extending hook 28 for engaging the upper edge of the front plate so that in securing it in place the upper edge of the front plate is engaged below the hooks 28 and fastening screws 29 are inserted through the plate into a boss 30 at the lower edge of the front of 35 the scupper. For additional protection the top plate or the front upper edge of the front plate 20 may be provided with a forwardly projecting package guard 31 which prevents a package of 40 any kind from being placed too close to the inlet of the scupper.

45 At the rear or discharge end of the scupper the casing as shown more clearly in Fig. 2 has an inclined edge 35 which normally seats a gate 36 hinged at its upper end on a hinge pin 37 in an overhanging extension 38 of the top plate. 50 A rush of water easily opens this gate 36 which allows it to discharge freely from the end of the casing and usually at a distance from the edge of the wall, and as soon as the water flow ceases 55 the gate will be closed by gravity.

Instead of a gravity gate as shown, the inner end of the casing may be turned downwardly as shown in Fig. 4, the casing 40 being shown as of continuous section and having a downward extension 41 with a flange 42 for the attachment of down pipes or other discharge means. A fixed casing of this kind is more properly applicable to a roof drain scupper, although either type of scupper is applicable for a roof or floor installation.

With this construction an emergency outlet is provided for the escape of an extra quantity of water or other liquid on the roof or any floor of a building which prevents damage due to the presence of an unexpected amount of liquid in case of a fire or the breakage of a pipe or tank containing liquid. When not in use the gates are automatically closed to form a dead air space between the inlet and discharge ends of the scupper and closing the wall against the flow of air or liquid in a reverse direction.

I claim:

1. A building scupper comprising a casing to extend through a wall with its lower edge at floor or roof level at the inside thereof, and a swinging door mounted upon a substantially upright pivot at one side of the casing and inclined so that the door is closable by gravity at the inside of the wall.

2. A building scupper comprising a casing to extend downwardly at an angle through the wall from a floor level, a grating mounted at the inner end of the casing and including pivot bearings substantially vertical but inclined inwardly at the top from the side of the opening, and a swinging door mounted on a pivot in the bearings and closable toward the center by gravity at the inside of the grating.

3. In a wall scupper, a casing having a grating at the inlet end, and a pair of gates mounted at the sides of the casing upon substantially upright axes inclined inwardly at the top so that the gates will close inwardly by gravity against the inside of the grating.

4. In a wall scupper, a casing to extend downwardly through a wall having a gate at the inlet and means for mounting the gate on a substan-

tially vertical axis extending inwardly and forwardly at the top of one side of the inlet opening so that the gate will tend to close the inlet opening by gravity.

5. In a scupper of the class described, a casing to extend through a wall having an overhanging projection at the top of the inlet end, a grating to fit over the inlet end of the casing having a notch at the top to engage under the said projection, and fastening means at the bottom of the grating to attach it to the lower edge of the casing.

6. In a wall scupper, a casing to extend through a wall and a grating for the inner end of the casing, a gravity closing gate mounted at the side of the casing and closable against the inside of the grating, and a package guard comprising a forward wavy extension of the grating at the top of the casing to space an obstruction therefrom.

7. In a wall scupper, a casing to extend through a wall having an inclined bottom and a flaring inlet with a substantially flat top, a pair of gravity closing gates each mounted at the side of the opening and meeting at the center, and means forming a substantially vertical axis inclined inwardly and forwardly at the top at each side of the opening so that the upper edge of each gate is substantially parallel with the top of the casing in open position, and inclines downwardly therefrom toward the center of the opening in its closed position.

8. In a wall scupper, a casing having its bottom inclined downwardly from the inlet to the outlet to project beyond the wall at the outlet end, a removable top for the casing having an overhanging projection at each end, a gate mounted in the overhanging projection at the discharge end to swing by gravity about a horizontal pivot, a grating engaging the overhanging projection at the top at the front end and secured to the casing at the bottom, and a pair of gravity closing gates mounted at the inside of the grating upon axes which incline forwardly and together at the top so that the gates tend to close the inlet by swinging downwardly against the inside of the grating.

ARTHUR J. FILKINS.
